By his Atty. *Thos. A. Drayton*

UNITED STATES PATENT OFFICE.

FREDRICK T. MAYNARD, OF DETROIT, MICHIGAN.

PILLOW-SHAM HOLDER.

SPECIFICATION forming part of Letters Patent No. 293,900, dated February 19, 1884.

Application filed November 21, 1883. (No model.)

To all whom it may concern:

Be it known that I, FREDRICK T. MAYNARD, of Detroit, in the county of Wayne and State of Michigan, have invented new and useful Improvements in Sham-Holders; and I do hereby declare that the following is a full, clear, and exact description thereof, reference being had to the accompanying drawing, which forms a part of this specification.

10 This invention relates to certain new and useful improvements in pillow-sham holders; and the invention consists in the peculiar construction, arrangement, and combinations of the various parts, all as more fully hereinafter set forth and claimed.

15 In the accompanying drawing, which forms a part of this specification, my invention is shown in perspective, in which A B represent two rectangular frames, each of which is preferably formed from a continuous wire bent to the desired shape, one end of each terminating in a loop or ring, *a*, while the other end is bent and embraces the wire just inside this loop, as at *b*.

20 C C are slides rigidly secured to the frame A at or near the inner bends, and embrace the horizontal sides of the frame B, and D D are similar slides secured to the frame B, and which embrace the horizontal sides of the frame 25 A, the two frames being thus secured together and adapted to slide upon each other, so that the holder may be adjusted in its length to the requirements of the bedstead upon which it is to be used. In practice the rings *a* engage 30 with any suitable brackets upon the head-board, which form no part of my invention,

and hence I neither show nor describe them. Upon the upper side bars of the frames I place rings, hooks, or other suitable devices, by means of which the shams may be secured upon 40 the holders.

I am aware of Patent No. 284,119, which shows two adjustable frames, three sides of each frame being of wire, while the remaining side is formed of wood, to which the wire is secured. This does not make as durable or 45 cheap a holder as one made after my improvement, for the wire is easily twisted, pulled, or accidentally broken from the wood, which will be likely to split, and as the wire parts are not 50 fastened together they are easily pulled out of shape, while mine, being made of two pieces of wire only, without wood-work, and braced by clips, makes a cheap, durable holder, and one that will retain its shape under all 55 circumstances and conditions.

What I claim as my invention is—

A pillow-sham holder consisting of two rectangular frames, A B, each formed from a continuous wire, one end of said wire being provided with a loop, *a*, adapted to hang the frame upon a bracket, and its other end formed with a loop, *b*, embracing and holding the end of the wire carrying the loop *a*, and adjustably secured together by the slides C D, embracing 60 both wires at top and bottom, substantially in 65 the manner and for the purposes specified.

FREDRICK T. MAYNARD.
